UNITED STATES PATENT OFFICE

2,506,135

DEVICE FOR EXHIBITING CHANGEABLY COLORED DESIGNS AND SUPPORTING FRAME THEREFOR

Eford Burchell, New York, N. Y., assignor to Burchell Holloway Corporation, New York, N. Y., a corporation of New York

Application November 19, 1946, Serial No. 710,864

3. Claims. (Cl. 88—65)

1.

This invention relates to color display devices and, more specifically, to a device for exhibiting changeably colored designs.

An object of the invention is to provide a device of this character which is simple and economical of construction, which can be rapidly, safely and conveniently manipulated, which will perform efficiently the purposes for which it is intended, and which can be readily manufactured, assembled and used.

Another object of this invention is to provide a device of this character in which sheets of material may be firmly held in substantially flat condition at all times under a proper tension, in which the sheets may be quickly and securely attached and as quickly detached, in which strains and vibrations are minimized and prevented from harming the sheets, in which certain of the sheets are rotatably mounted and in which the main structure is simple and not cumbersome.

Another object of the invention is to provide novel means for demountably supporting sheets of material in substantially flat condition, and to provide for expansion and contraction of the sheets of material while keeping them flat.

With these and other objects in view, the invention comprises the features of construction, combination of elements and arrangement of parts hereinafter to be described and then sought to be defined in the appended claims, reference being had to the accompanying drawings forming a part hereof, wherein a preferred embodiment of the invention is shown; for the purposes of illustrative disclosure, it being expressly understood, however, that changes may be made in practice within the scope of the claims without digressing from the inventive idea.

In the drawings—

Fig. 1 is an elevational view of a device embodying the invention;

Fig. 2 is a vertical section taken along line 2—2 of Fig. 1 and viewed in the direction of the arrows;

Fig. 3 is a fragmentary elevation of the demountable sheet supporting means of the invention;

Fig. 4 is an enlarged section taken along line 4—4 of Fig. 3 and viewed in the direction of the arrows;

Fig. 5 is an elevation on a reduced scale of the opposite side of the structure of Fig. 3; and

Fig. 6 is an enlarged sectional detail of a structural variation.

Referring to the drawing, 10 denotes a casing

2.

having an open front. One or more lights 11 and reflectors 12 are supported or secured in the casing 10. A motor 13 is secured to the casing 10 and coupled, for example, through a gear box 14 with a drive-shaft 15. A roller 16 having an annular groove 17 is keyed or otherwise fixed on the shaft 15. Two or more additional rollers 18 each having annular grooves 19 are rotatably secured within the casing so that their grooves 19 and groove 17 of roller 16 are co-planar.

The demountable sheet supporting means comprises an annular mounting ring 20. This ring or frame-like member is borne in the grooves 17 and 19 of the rollers 16 and 18. The spindle 21 of at least one of the rollers is pivotally supported at 22 and spring actuated in conventional manner (not shown), so that it may be swung out of engagement with the periphery of ring 20 to facilitate removal of the latter. When it is in engaging position, however, with the ring, it holds the ring in place on the rollers. The weight of ring 20 will maintain a frictional engagement between the surface of the groove in roller 16 and the peripheral surface of the ring 20 so that the latter will rotate in its plane when the roller 16 is driven by motor 13.

The ring 20 has an annular or perimetrical laterally extending flange 23. This flange has an annular or perimetrical groove 24 in one face. The innermost wall 25 of the groove 24 has a plurality of regularly spaced openings 26 for purposes presently described. An endless-stretchable member or spring 27 admeasured to fit the groove 23 is provided. This spring 27 must be stretched for insertion into the groove 23.

The material that is secured on the ring 20 consists, for example, of a sheet 28 of isotropic translucent material as matte cellulose acetate and a sheet 29 of polarizing material. The sheets 28 and 29 are joined together as by cement. At 40 a number of points eyelets 30 are secured to the joined sheets. These eyelets correspond in number to the spaces 26 in wall 25. Hook-like securing members 31 attached to eyelets 30 extend laterally from the latter in the radial direction. 45 These securing members are admeasured to extend into the spaces 26 and to hook around the spring 27. When so hooked they deform the spring 27 under tension sufficiently to draw the latter somewhat into the spaces 26 and when 50 all are in place, the spring tension created by these deformations tends to maintain the joined sheets 28 and 29 flat and in place on the ring 20.

Ready removal of the sheets, if desired, is effected by simply removing the spring from the groove 24. If it is desired, the inner wall 25 of

the groove may be bent inwardly to retain spring 27 in the groove 24 (Fig. 6).

A second sheet 33 of polarizing material is conveniently and removably secured over the open front of the casing 10 as by the screws 34 or in any other desirable way. Intermediate the ring-borne sheets 28 and 29 and the outermost sheet 33, a sheet 35 of translucent isotropic material of the same kind as sheet 28 is removably mounted as by screws 36 to a fixed frame support 37. This sheet carries designs D of birefringent material, prepared for example as specified in Burchell and Ivins Patent No. 2,393,968, granted February 5, 1946, or in other suitable ways. Sheet 35 may be otherwise supported as hereinafter described.

The operation of the device is clear. When the motor rotates ring 20, its spring mounted polarizing sheet 29 is also rotated so that the plane of polarization of the light from source 11 is constantly changing direction. Hence that light which continues out through the birefringement design D and the outer polarizing sheet 33 whose axis of polarization is fixed, changes constantly from one color to its opposite through colors which are mixtures of those colors.

If desired, the design bearing sheet 35 and sheet 33 may each be supported by a ring exactly like the ring 20. These rings, however, would be supported fixedly from the casing 10 rather than rotatively. Moreover, the ring 20 supporting sheets 28, 29 could be stationary and, instead, a ring like ring 20 could be used to support rotatably a sheet 33. Such a ring would be driven in the same way as ring 20. The ring 20 may have other shapes than circular if desired.

While specific embodiments have been shown and described, variations in structural detail are possible and are contemplated. There is no intention of limitation to the exact details shown and described.

What is claimed is:

1. A device for supporting sheet material in substantially flat condition comprising a frame-like member having a perimetrical groove in one face and openings in the inner side wall of said groove, an endless stretchable member removably mounted in said groove, hook-like securing members permanently attached to said material and extending outwardly thereof and substantially radially into said openings and being there engaged removably with said stretchable member.

2. A device for demountably supporting sheet material in substantially flat condition and to

provide for expansion and contraction of the sheets of material while keeping them flat comprising a ring-like member having an annular groove in one face and openings in the inner side wall of said groove, an endless spring removably mounted in said groove, hook-like members attached permanently to said material and extending radially thereof into said openings and there being hooked removably about said spring and 10 when so hooked deforming the spring under tension sufficiently to draw the latter somewhat into the openings, the tension created by the deformation maintaining the sheets flat and in place on said ring-like member.

3. In a device of the character described, means for demountably supporting sheet material in substantially flat condition and to provide for expansion and contraction of the sheet material while keeping it flat comprising a frame-like member having an annular groove in a side face and openings in the inner side wall of said groove, an endless elastic member removably mounted in said groove, hook-like members, pivotal means for permanently supporting said hook-like members from said sheet material to extend substantially radially of said sheet material and into said openings, said hook-like members being removably hooked about said spring substantially within said openings and when so hooked deforming the elastic member under tension sufficiently to draw the latter somewhat into the openings, the tension created by the deformations maintaining the sheet material flat and in place on said frame-like member.

FFORD BURCHELL.
